UNITED STATES PATENT OFFICE.

EMIL EIGNER, OF NEW YORK, N. Y.

MACHINE FOR PRINTING MEASURING-TAPE.

No. 895,079.

Specification of Letters Patent.

Patented Aug. 4, 1908.

Application filed May 31, 1907. Serial No. 376,477.

To all whom it may concern:

Be it known that I, EMIL EIGNER, a citizen of the United States, and residing at New York, in the county of New York and State 5 of New York, have invented certain new and useful Improvements in Machines for Printing Measuring-Tape, of which the following is a specification, such as will enable those skilled in the art to which it appertains to make and 10 use the same.

This invention relates to machines for printing a scale on a measuring tape designed to be rolled with a ribbon or other strip of flexible material into a roll in order that the 15 exact amount of ribbon or other material in the roll may be determined at any time, whereby a retail dealer in goods of this class may determine at any time the amount of goods remaining in the roll after a part thereof has been sold and also determine when purchasing goods of this class from the wholesale dealer the amount of goods contained in the roll.

The invention is fully disclosed in the following specification, of which the accompanying drawing forms a part, in which the separate parts of my improvement are designated by suitable reference characters in each of the views, and in which:

30 Figure 1 is a side view of my improved machine; Fig. 2 a front view thereof; Fig. 3 a back view thereof; Fig. 4 a plan view; Fig. 5 a view similar to Fig. 2 showing a part of the construction on an enlarged scale; Fig. 6 a 35 view looking in the direction of the arrow 6 of Fig. 5; Fig. 7 a section on the line 7—7 of Fig. 5; Fig. 8 a section on the line 8—8 of Fig. 2, and showing the parts in a different position and on an enlarged scale; and, Fig. 9 40 a face view of a part of a measuring tape having a scale printed thereon by my improved machine.

In the practice of my invention, I provide a frame of the following construction. Connected with a base a is a main upright member a^2 of predetermined height, and secured to the base member a adjacent to the main upright member a^2 is a supplemental upright member a^3 of much less height than the main 45 upright member a^2 . Secured to the top portion of the main upright member a^2 by bolts, bars or any suitable devices a^4 is a hanger a^5

which forms a part of the frame and which corresponds in position with the upright member a^4 and is in vertical line therewith. 55 Placed in the frame thus formed and resting on the main upright member a^2 and connected with the main upright member a^2 in any desired manner is a table c which, in effect, forms a part of the frame of the machine. Mounted in the bottom portion of the frame thus formed is a shaft b on which is mounted a roller or wheel b^1 , said shaft and wheel being placed below the table c and the table c projects at right angles to the frame 60 and to a predetermined distance from said frame.

Mounted in the top portion of the frame formed by the parts a^2 and a^5 is a shaft d on which is mounted a wheel e comprising, in 70 the form of construction shown, a rim member e^2 , spokes e^3 and a hub e^4 . The rim of the wheel e , as clearly shown in Figs. 1, 6 and 7, is provided with an annular groove e^5 in which is placed a scale band f designed to 75 print on a tape, a scale representing yards and fractions thereof and inches and fractions thereof. By forming the scale on a band secured in a groove in this manner, the construction of the main printing wheel is 80 cheapened and I am enabled to change or renew the scale with little loss of time or expense. One side of the rim e^2 of the wheel e is cut as shown at e^6 to form a recess in 85 which is mounted a wheel g , the face or perimeter of which is provided at intervals with notches or recesses g^2 , and the outer side of which is provided at corresponding intervals with projecting pins g^3 , the pins g^3 being placed between the notches or recesses g^2 and 90 being arranged in a circle on the side of the wheel g . Pivoted in the recess e^6 is a pawl h provided at one end with a nose h^2 adapted to enter the recesses g^2 in the wheel g , and at the opposite end of which is a spring h^3 which 95 bears on the inner side of said pawl and normally serves to force the nose h^2 thereof into the recesses g^2 .

At the top of the main frame and mounted in laterally extending arms i is an inking roller i^2 which normally bears on the wheel e or on the scale printing band f . The table c is provided with a guide clamp f which is movable longitudinally thereof and adapted

to be secured at any desired point thereon by means of a set screw j^2 . I also provide the table with a spring presser plate k which is secured to the inner end of the table at k^3 and 5 extends outward to the end of the table along the right side of the same. The front edge of this presser plate curves upwardly as shown at k^2 to facilitate the introduction and 10 passage of the material to be printed beneath it. The underside of the top portion of the clamp j is recessed to admit the presser plate beneath it and permit such movement as will occur in the operation of the machine.

The wheel g bears on its face at regular intervals 15 the numerals one, two, three etc., as shown at g^4 which are intended to print on the measuring tape, and while the scale band f prints on said tape the fractions of yards and inches and fractions thereof, the wheel g 20 prints thereon the number of the yards, and my improved machine, as constructed, is intended to print a measuring tape ten yards long, and the wheel g therefore bears the numerals from one to ten.

25 At the top of the main frame of the machine, or at the top of the upright member a^3 thereof, is secured a plate o provided with a projecting pin o^2 which at each complete revolution of the wheel e engages one of the 30 pins on the wheel g and moves said wheel g against the retarding influence of the pawl h one step, and a new yard is printed on the tape m , and at the beginning of each yard printed by the wheel g on the tape m the 35 inches and fractions of inches of the new yard also begin as clearly indicated in Fig. 9.

The wheel e , or the shaft or axle d thereof, is provided with vertically movable bearings p mounted in the parts a^2 and a^5 of the main 40 frame, and these bearings and the means for adjusting the same may be constructed in any desired manner, the object thereof being to regulate the pressure of the wheel e on the wheel or roller b^2 between which the tape m is fed, and in this operation the wheel or roller b^2 works in a transverse slot r in the table c as indicated in dotted lines in Figs. 2 and 3 and as shown in section in Fig. 1.

In Fig. 9, I have shown at m a measuring 50 tape printed by my improved machine and, in practice, the tape is fed into the machine as indicated in Figs. 2 and 3, the end thereof being passed beneath the spring presser plate k in line with the plane of the wheel e and directly under said wheel. The wheel e is then turned by means of the crank n and the desired scale is printed on the tape m as will be readily understood. In this operation the wheel g prints the yards from one to ten 55 60 on the wheel e or the scale band f thereon prints the inches and fractions of inches and fractions of yards as shown in Fig. 9. The part of the measuring tape shown in Fig. 9 is

taken from the central portion of said tape and the figure five thereon at m^2 represents 65 the fifth yard, the remaining portion of the scale representing inches and fractions thereof and fractions of a yard, the fractions of yards shown being an eighth and a quarter.

The clamp j in addition to serving as a 70 means for holding the outer end of the guide plate k in proper position also serves as a guide for the tape or strip on which the scale is to be printed, and said clamp may be adjusted to any desired position according to 75 the width of said tape or strip. It will also be seen that the frame of the machine at the side thereof, adjacent to the table c , or over said table is open so as to permit the said tape or strip to be fed through the machine 80 in the operation of printing the scale; and while I have shown and described a particular form of frame in order to accomplish this result, it will be apparent that changes therein and modifications thereof, within the 85 scope of the appended claims, may be made without departing from the spirit of my invention or sacrificing its advantages. It will also be observed that the wheel g , in the operation of the machine as herein described, 90 is supplemental to the wheel e , and while said wheel g turns therewith it also is capable of independent rotation, and in the operation of the machine the said wheel g must be adjusted so that the numbering of the separate 95 yards on the tape or strip on which the scale is printed will begin at the proper time, or when the printing of the inches and fractions of inches and fractions of yards by the wheel e begins.

Having fully described my invention, what I claim as new and desire to secure by Letters Patent, is;—

1. In a machine for printing on a flexible material, the combination with a suitable 105 supporting frame, of a main printing wheel mounted in said frame, a supplemental printing wheel mounted on the main printing wheel, said supplemental printing wheel being provided on its perimeter with notches 110 or recesses, a spring pawl engaging said notches or recesses to prevent accidental rotation of said supplemental printing wheel in either direction, the rim of said supplemental printing wheel being also provided with laterally projecting pins, and the frame provided with a finger extending into the path of said pins for engaging and moving the said supplemental printing wheel one step at each revolution of the main printing wheel, substantially as described.

2. In a machine for printing on flexible material, the combination with a suitable supporting frame, of the printing mechanism, a table, an adjustable guide clamp on said 125 table, and a spring presser plate secured to

the table and extending beneath the upper part of said guide clamp, the upper part of said guide clamp being provided with a recess to accommodate said presser plate, substantially as described.

In testimony that I claim the foregoing as my invention I have signed my name in pres-

ence of the subscribing witnesses this 29th day of May, 1907.

EMIL EIGNER.
